TANGENTIALLY FINNED HEAT EXCHANGE
TUBE

André Huet, Paris, France

Application April 6, 1950, Serial No. 154,213

1 Claim. (Cl. 257—262.19)

1

This invention relates to heat exchangers and particularly to an improved form and arrangement of tubes provided with integral longitudinal fins as extended surface.

In an earlier application, Serial No. 748,561, filed May 16, 1947, now Patent No. 2,578,136 dated December 11, 1951, of which this is a continuation-in-part, applicant has described finned heat exchange tubes each provided with two longitudinally disposed fins located approximately diametrically opposite each other with the planes of the fins being tangent to the surface of the tube which is swept by the exterior fluid flowing in a direction perpendicular to the axis of the tubes.

One of the advantages resulting from this arrangement is that when an exchanger has a bundle of such tubes disposed in staggered relation, there are formed between the tiers of tubes sinuous channels of variable section whose boundaries are determined by the fins and the surfaces of the tubes. The exterior fluid flows in these sinuous channels which, because of the disposition adopted for the fins and tubes, present restrictions and enlarged parts, these variations of section assuring variations of pressure and of speed in the flow of exterior fluid, as well as changes in directions of flow, which contributed favorably to the efficiency of the heat exchanger.

As a result of tests and experience with heat exchangers provided with tangentially finned tubes of the type described above, it has been discovered that it is possible to further increase the efficiency of the heat exchanger if the channels between the tiers of tubes present upstream of each restriction a channel boundary such that the section offered to the passage of the exterior fluid enlarges gradually up to the next restriction or change in direction in the channel.

Consequently, the present invention relates particularly to heat exchangers made up of tubes provided with specially shaped tangential fins which on adjacent tubes cooperate to present channels having successive restrictions and/or changes of direction followed by gradual enlargements of the section provided for the passage of the fluid. These are in the general form of a divergent up to the next restriction or change of direction of the passage afforded for the flow of fluid.

When the exchanger is made up of a bundle of parallel tubes disposed in staggered relation and provided with tangential fins as mentioned above, the tangential fins which define part of the boundaries of the channels that are offered to the flow of the exterior fluid are suitably thick.

2

ened and profiled or shaped in such fashion that in combination with the staggered disposition of the tubes the channel section afforded for the flow of exterior fluid enlarges gradually from one restriction of a channel to the following restriction.

The increase of efficiency obtained by the arrangement outlined above results from the following considerations: when a fluid circulates at a certain speed in a passage of constant section, the laminar flow of the fluid changes at the end of a certain distance of travel into a turbulent flow which provokes cavitations while a film of fluid remains adherent to the boundaries of the passage. In the case of a heat exchanger tube bundle where the exchange of heat is between two fluids flowing respectively exteriorly of the tubes and within them such a fluid film on the external surface of the tubes has the effect, since it is not replaced by fresh fluid, of diminishing the exchange of heat and, consequently, decreasing the efficiency of the heat exchanger. On the other hand the cavitations and turbulence increase the draft loss in the exchanger.

When in accordance with the invention, the channels traversed by the exterior fluid present successive restrictions followed by progressive dilations of the section of a channel formed between two slightly divergent boundary surfaces there is maintained a mode of fluid flow at relatively high rates of flow that eliminates the formation of turbulence throughout the entire length of the fluid passage.

In effect, the restriction of section presented to the flow of the fluids produces, at the moment when the flow would tend to become turbulent, a reaction which assures the maintenance of proper flow for the efficient exchange of heat which it again attains throughout the length of the divergent that follows the restriction etc. Thanks to the maintenance of this favorable flow along the whole length of the fluid passage, the fluid film in contact with the boundaries is diminished and constantly renewed without producing substantial cavitations or turbulence and the renewal of this film of fluid assures in the case of a heat exchanger an increase of efficiency since the exchange of heat can then be effected more easily between fluids flowing from one part to another of the boundary.

The figure shows in section a portion of a tube bank in a heat exchanger having tangentially finned heat exchange tubes in accordance with the present invention.

The tubes 10 are arranged in parallel rows.

whose axes, such as X-X, Y-Y, Z-Z in the figure, are shown as inclined across the gas stream at an angle to the general direction of flow through the passage as indicated by the arrows A. Each tube 10 is provided with two flat longitudinally extending fins 20 and 21 welded at 180° with respect to each other on the periphery of the tube and projecting in directions approximately tangential to the surface of the tube. One side face 11 of each fin 20, 21 is flat or planar and substantially tangential to the tube while the opposite face 12 is concavely curved from the distal end 13 of the fin to its junction 14 with the tube, at which point it is substantially tangential; i. e. the arc of its surface and that of the tube meet on a tangent. The finned tubes are more or less symmetrical since the downstream fins 21 while similarly profiled are disposed with their curved and planar surfaces oppositely arranged to those of the upstream fins 20. As shown in the drawing the tubes 10 are arranged at equal intervals in staggered relation in uniformly spaced parallel rows and disposed in such fashion in the gas passage that the fins 20, 21 are on the upstream and downstream faces of the tubes and slightly inclined with respect to the general direction of the heating gas current which follows the direction of the arrow A. This inclination could be eliminated and the fins 20, 21 located parallel to the direction of gas flow which is indicated by arrow A.

With the arrangement described above, the main fluid stream flowing in the direction of arrow A is split up by the upstream fin 20 so that the left hand current comes into contact with the tube 10 as indicated by the arrow B (lower right in the figure) and wipes against about 120° of its surface. At the moment, when conforming to conventional aero-dynamic theories, the stream should begin to flow around the back face 22 of tube 10 and create a void with eddy currents, it has reached the base 15 of the fin 21 which it sweeps over on the left hand face 11A in the direction of the arrow C. On the right hand face 11 of the upstream fin 20 the fluid current which follows the arrow D wipes against about 120° on the right hand face of the tube 10 and in following the arrow E curves against the back of the tube and is finally turned away by the right hand face 12A of the downstream fin 21 so as to follow the arrow F.

It may be seen that with this arrangement the entire surface of a tube 10 and its fins 20, 21 is scoured by the currents of hot gases and consequently an optimum heat exchange is assured.

From one row to another of tubes in the heat exchanger the fins can be disposed parallel in similar fashion or can be alternated so that upstream fins are first on the right, then the left etc. With the tubes spaced at like distances in each row and the fins in corresponding locations on the tubes, the upstream fin 20 on tubes of one row align with and are in approximate contact with the downstream fins 21 in a following row. The distal ends 13 of the fins may be close together or actually in contact to form separated gas lanes. The fins on tubes in adjacent rows may be in approximate contact at a point in a plane "T" parallel to the general direction of flow and passing through or close to the axis of the tube. The arrangement shown places the tube bodies in the intermediate rows opposite the distal ends of fins on tubes in the immediately following and preceding rows. This narrows the gas lanes at H and widens them at N. Thus,

the entire width of the heat exchange pass is divided into a number of sinuous channels made up of alternately narrowing parts H followed by widened parts N in continuous series through the bank. In passing through the narrow sections H the velocity of the stream increases and then upon expanding in the widened sections N the energy obtainable is converted from velocity to static pressure so that the streams completely fill the channel spaces between the tubes and the heating gas flows in intimate contact with the tubes and their fins to assure the most efficacious heat transmission between the gas and the fluid flowing through the interior of the tubes 10.

As is seen, these channels between tiers of tubes are of varied section and present restrictions H and/or changes in direction located for example at the height of the plane passing through the axis of the two tubes 10A, 10B (lower right) corresponding in neighboring tiers. According to the invention the surface of the tangential fins are such that beginning with one restriction H and continuing to near the restriction H located downstream therefrom the channel affords to the fluid A a gradual divergent between the boundary lines GK on one side and LP on the other side. To give to the channel part located beyond each restriction H this divergent boundary GK, LP the tangential fins mounted on the upstream and downstream sides of the tubes have different profiles, the lower fins 21 for example, being slightly thicker than the upper fins 20.

The downstream fin 21 on a tube is stated as being thicker than the upstream fin 20 hence while the fins are mounted at diametrically spaced points on the tubes the increased thickness of the lower fins 21 at the point of juncture with the tube causes the planar portion 11A of the downstream fin 21 that is included in the boundary surface GK to diverge slightly from parallelism with the confronting flat surface 11 of the tangential fin on the top or upstream side of the tube in the adjacent row thereby gradually increasing the section of the passage from a point where the downstream fin 21 is tangent to the tube to a point where the distal end of the fin is in substantial alignment with the edge of the upstream fin 20 on the tube below.

What I claim is:

In a heat exchanger having a passage through which gases flow over tubes spaced in parallel rows located in planes perpendicular to the gas flow with the tubes in adjacent rows staggered and dividing said passage into a number of sinuous gas lanes; longitudinally extending fins on the upstream and downstream sides of the tubes each having a planar face tangential to its tube with the other face of each fin concavely curved from its distal end to its junction with the tube at a point where said curved face becomes substantially tangential, the downstream fin on each tube being tangential thereto at a point slightly more than 180° from the planar face of the upstream fin and its other face being curved on a greater radius than that of the upper fin with the faces of the downstream fin disposed reversely to those of the upstream fin so that planar faces of fins on tubes in one row confront planar faces of fins on the tubes in rows upstream and downstream thereof out of parallelism therewith and bound sections of the gas lanes that are gradually enlarged in the direction of flow while the curved face of a fin confronts tube surfaces opposite and between the two fins on a tube in an

adjacent row, the distal edge of the planar face of the downstream fin on each tube being substantially in alignment with the corresponding distal edge of the curved face of the upstream fin on a tube therebeyond substantially in a plane lying parallel to the general direction of flow and passing substantially through the axis of said adjacent tubes and the said downstream fins being thicker at their distal ends than the upstream fins and tapering to their roots at the 10 tube surfaces so that gas lanes opposite the curved faces of said downstream fins are narrower than lanes bounded by the more sharply curved faces of upstream fins.
